Term of patent 14 years

(Cl. D92—1)

2 2

Fig. 1 is a plan view of a textile fabric, showing our new design; and

Fig. 2 is a sectional view of the fabric of Fig. 1 along the line 2—2.

The design is embodied in a textile fabric having a surface of raised puffs appearing as light areas in Fig. 1. In the embodiment shown, the puffs are held raised by threads interlaced in the fabric; these threads are represented by the straight line in Fig. 2.

We claim:

The ornamental design for a textile fabric, as shown and described.
